Fig. 7

Fig. 8

FIG. 9FIG. 10FIG. 11FIG. 12FIG. 13FIG. 14

FIG. 1 is a front perspective view of a convertible seat showing my new design;

FIG. 2 is a top plan view of the convertible seat of FIG. 1;

FIG. 3 is a rear perspective view of the convertible seat of FIG. 1;

FIG. 4 is a front perspective exploded view of the convertible seat of FIG. 1;

FIG. 5 is an exploded top plan view of the convertible seat of FIG. 1;

FIG. 6 is a front perspective view of the convertible seat of FIG. 1 as it is being folded over for converting into a bed or similar article;

FIG. 7 is a perspective view of the convertible seat of FIG. 1 converted into a bed or similar article;

FIG. 8 is a top plan view of FIG. 7;

FIG. 9 is a front perspective view of a second embodiment of the convertible seat of FIG. 1;

FIG. 10 is a top plan view of the convertible seat of FIG. 9;

FIG. 11 is a rear perspective view of the convertible seat of FIG. 9;

FIG. 12 is a front perspective view of the convertible seat of FIG. 9 being folded over for converting into an ottoman or similar article;

FIG. 13 is a perspective view of the convertible seat of FIG. 9 converted into an ottoman or similar article; and

FIG. 14 is a top plan view of FIG. 13.

This is a continuation of design application Ser. Nos. 501,624 and 501,627, both filed Aug. 29, 1974, both now abandoned.

I claim:

The ornamental design for a convertible seat or similar article of furniture, substantially as shown.
